UNITED STATES PATENT OFFICE.

EUGENE L. BAKER, OF TAUNTON, MASSACHUSETTS.

STOVE OVEN.

1,426,032.

Specification of Letters Patent. Patented Aug. 15, 1922.

Application filed January 17, 1921. Serial No. 437,868.

To all whom it may concern:

Be it known that I, EUGENE L. BAKER, a citizen of the United States, residing at Taunton, in the county of Bristol and State 5 of Massachusetts, have invented a new and useful Stove Oven, of which the following is a specification.

This invention aims to provide a foldable deflector for use in a stove in which either 10 gas or solid fuel is employed, the deflector forming means for raising and lowering a member which closes the air inlet, said member being so constructed that it cannot serve as a deflector, and there being no deflection 15 of the heat, in the absence of the foldable deflector above alluded to.

It is within the province of the disclosure to improve generally and to enhance the utility of devices of that type to which the 20 invention appertains.

With the above and other objects in view, which will appear as the description proceeds, the invention resides in the combination and arrangement of parts and in the 25 details of construction hereinafter described and claimed, it being understood that, within the scope of what is claimed, changes in the precise embodiment of the invention shown can be made without departing from 30 the spirit of the invention.

In the accompanying drawings:—

Figure 1 shows in vertical section, a stove oven equipped with the device forming the subject matter of this application, the deflector being lowered; Figure 2 is a view 35 similar to Figure 1, the deflector being raised and folded; and Figure 3 is a section on the line 3—3 of Figure 1.

The stove in which the invention is 40 embodied, may be constructed variously. Therefore, the stove structure will be described somewhat briefly, those parts only being alluded to, which have some function in connection with the device forming the 45 subject matter of this application.

In the drawings there is shown a stove oven defined by walls 1 and 2 disposed opposite to each other, and by walls 3 and 4, likewise disposed opposite to each other, the 50 wall 4 having an offset portion 5. The top of the oven is shown at 6 and the bottom thereof appears at 7. Walls 8 cooperate with the bottom 7 and constitute a part of an air inlet 9. The oven has an outlet for

the products of combustion, the outlet being 55 designated generally by the numeral 10. The outlet is formed by a plate 11 connected at one end to the top 6 and connected at its other end to the wall 4, the plate having an opening 16 disposed at some distance 60 from the wall 4. The outlet 10 is bounded, also, by a wall 12 disposed approximately parallel to the rear end portion of the top 6. A partition 14 extends across the outlet 10 in alignment with the wall 4. There is 65 an opening 15 in the partition 14, an opening 20 being formed in the part 12, the opening 20 communicating with the atmosphere. Bearings 17 are located in the angle defined by the wall 4 and by the upper portion of the part 5. A check-draft damper is mounted to rock in the bearings 17 and comprises leaves 18 and 19, disposed at an angle to each other. The leaf 18 controls 70 the opening 15, the leaf 19 controlling the opening 20. The leaf 19 is provided with an angular finger 21 projecting through an aperture 22 in the part 5. The numeral 23 designates a source of fuel supply discharging 75 into a sleeve 24 constituting a part of 80 the casing of the oven, the numeral 25 marking an air-regulating damper at the outer end of the sleeve 24.

Disposed within the oven is a deflector 26 comprising parts 27 and 28 united by 85 hinges 29. The part 27 of the deflector 26 is supplied with a socket 30 adapted to receive an ordinary stove lid lifter, (not shown) made use of when the deflector is folded or unfolded, as hereinafter described. 90 The part 28 of the deflector carries depending ears 31 pivoted at 32 to the walls 1 and 2. When the deflector 26 is opened, as shown in Figure 1, the deflector is supported on brackets 33 projecting from the walls 1 95 and 2.

Levers 34 are fulcrumed, intermediate their ends, as indicated at 35, on the walls 1 and 2, the inner end of each lever being upwardly extended as indicated at 36, the 100 ends 36 of the levers being adapted to cooperate with the part 28 of the foldable deflector 26. In the outer ends of the levers 34, seats 37 are fashioned, the same being adapted to receive hangers 38 on a member 105 39, which may be a burner, said member being so shaped that when it is lowered, it will seat in the upper end of the air inlet 9 and

render the bottom of the oven continuous. The member or burner 39 includes a tubular part 40 having a flange 41 adapted to engage beneath the inner end of the sleeve 24. 5 The member or burner 39 has side combustion orifices 50 located at the extreme outer edges of the burner. No portions of the burner 39 project beyond or overhang the orifices 50, and the burner has absolutely no 10 means whatsoever for deflecting the flame proceeding from the orifices. The deflection is accomplished solely by the member 26, when the member 26 is lowered, as shown in Fig. 1, and the burner 39 has no function 15 as a deflecting means. When coal, wood or any other solid fuel is used, the parts are arranged as shown in Figure 2. Then, the member 39 is seated in the upper end of the air inlet 9. The parts 27 and 28 of the 20 deflector are folded together on the hinges 29, and the deflector is swung rearwardly on the pivot elements 32, into the offset portion 5 of the wall 4. The part 28 of the deflector engages the finger 21 of the damper 25 and causes the leaf 19 to close the opening 20, the leaf 18 closing the opening 15.

When gaseous fuel is to be used, the deflector 26 is opened and swung downwardly, into the position shown in Figure 1. Under such circumstances, the ends 36 of the levers 34 are engaged by the part 28 of the baffle and the forward ends of the levers are raised, the member 39 being elevated out of the upper end of the air inlet 9. When the 35 member 39 is raised, the flange 41 on the part 40 engages beneath the sleeve 24, as shown in Figure 3. Since the finger 21 no longer is engaged by the part 28 of the deflector 26, the finger swings downwardly, 40 moving the leaf 19 away from the opening 15. There is, therefore, no appreciable drag on the heated air within the oven, the draft being cut down because air can enter through the opening 20. At the same time, 45 since the opening 15 is uncovered, the products of combustion may pass away, without any appreciable suction.

Having thus described the invention, what is claimed is:—

1. In a device of the class described, an 50 oven having an air inlet in its bottom; a member forming a closure for the inlet and rendering the bottom continuous; means for lifting said member to open the inlet; and a deflector mounted to swing in the oven 55 over and away from said member, the deflector engaging and actuating said means when the deflector is swung over said member.
2. A device of the class described, constructed as set forth in claim 1 and further 60 characterized by the fact that said member is a burner.
3. A device of the class described, constructed as set forth in claim 1 and further 65 characterized by the fact that the means for lifting said member consists of a lever, said member being carried by one end of the lever, the deflector engaging the other end 70 of the lever, and the lever being fulcrumed 75 intermediate its ends.
4. A device of the class described, constructed as set forth in claim 1 and further characterized by the fact that the oven has 80 an outlet and a check-draft opening communication therewith; a damper controlling the check draft opening, the dampers being connected for simultaneous movement, the dampers opening automatically when the deflector is disposed over said member, the 85 damper being provided with a finger disposed in the path of the deflector, whereby when the deflector is swung away from said member, the dampers will be closed by the deflector.

In testimony that I claim the foregoing as my own, I have hereto affixed my signature in the presence of two witnesses.

EUGENE L. BAKER.
